UNITED STATES PATENT OFFICE.

FREDERICK G. SHULL, OF NEW HAVEN, CONNECTICUT, ASSIGNOR TO ALUMINUM SEAL COMPANY, OF PITTSBURGH, PENNSYLVANIA, A CORPORATION OF PENNSYLVANIA.

BOTTLE CLOSURE.

Application filed November 16, 1922. Serial No. 601,273.

To all whom it may concern:

Be it known that I, FREDERICK G. SHULL, a citizen of the United States, residing at New Haven, in the county of New Haven 5 and State of Connecticut, have invented certain new and useful Improvements in Bottle Closures; and I do hereby declare the following to be a full, clear, and exact description of the invention, such as will 10 enable others skilled in the art to which it appertains to make and use the same.

The present invention relates to closures of the removable type which are employed for the purpose of sealing receptacles containing liquid or dry ingredients.

A well known form of removable seal employed more particularly in connection with glass receptacles embodies an outer sealing capsule of aluminum having a rupturing 20 tongue and a sealing flange crimped about the bead surrounding the mouth of the receptacle. This outer sealing capsule overlies an inner sealing disk of compressible material and a sheet metal disk interposed between the compressible disk and the sealing capsule. This form of closure provides a hermetically tight seal for the receptacle which will preserve the contents for an indefinite period and may be easily removed 25 without the employment of any special instrumentalities, the provision of the rupturing tongue permitting the outer capsule to be torn off and the inner disks to be completely and easily removed from the receptacle. This form of closure, however, does 30 not provide for resealing the container after the original seal has been removed therefrom. In many cases, such a resealing feature is a desirable adjunct of a closure in 35 order that foreign matter may be prevented from contaminating the contents during use.

It is accordingly the object of the present invention to produce a new and improved form of closure having all of the advantages 40 of the form of closure above described and with the additional advantage of a resealing feature which may be employed after the removal of the original seal.

With this object in view the feature of 45 the invention contemplates the combination with an outer sealing capsule of thin sheet material having a rupturing tongue and a depending sealing flange of an inner sealing disk of compressible material pressed 50 against the mouth of the receptacle, and a

secondary closure or seal interposed between the sealing disk and the outer capsule and having a substantially straight annular flange which projects downwardly over the bead upon the receptacle a sufficient distance 60 to maintain the secondary seal and disk in place after the removal of the outer seal. Although the flange upon this secondary seal, as stated, is of sufficient length to maintain the seal in place upon the mouth of 65 the bottle, it terminates short of the base of the bead and is not crimped in and secured with the flange of the outer capsule.

In the accompanying drawings illustrating the preferred form of the invention 70 Fig. 1 represents a section in elevation of the neck of the glass receptacle with the improved form of closure applied thereto; Fig. 2 is a view similar to Fig. 1 illustrating the resealing portion of the closure with 75 the outer capsule removed; and Fig. 3 is a section in elevation of the closure before application to the receptacle.

The illustrated embodiment of the invention is applied to a glass receptacle or bottle having the usual neck portion indicated at 10 terminating in a round mouth portion surrounded by a sealing bead 12 and sealing recess 14. The closure, as indicated, comprises an outer sealing capsule 16 of aluminum or similar sheet material having an integral rupturing tongue 18 and a depending sealing flange 20, which is crimped and bent along its lower edge 22 into the circumferential recess 14, as indicated clearly 80 in Fig. 1. The outer sealing capsule overlies an inner disk 24 of compressible material, which in turn is received within a secondary seal or capsule 26 having a relatively shorter depending flange 28, which 85 fits closely about the bead 12 and embraces a sufficient portion of the bead to insure its retention upon the mouth of the bottle after the outer capsule has been removed, as indicated clearly in Fig. 2. Upon the removal of the outer capsule by engagement 90 of the rupturing tongue 18 and tearing off the capsule therewith, the inner or secondary capsule 26 is exposed and this capsule 95 may be readily removed to permit the contents to be drawn from the receptacle. Thereafter the capsule may be replaced and constitutes a resealing of the bottle which prevents the entrance of foreign matter out- 100 side of the receptacle. It will be evident 105

110

to those skilled in the art that this resealing does not provide a hermetic seal for the contents but does serve as a simple and efficient closure for the open mouth of the bottle, which does not interfere with the application of the original seal or its removal when the contents are to be used. From an inspection of Fig. 3, it will be noted that the sealing flange 20 upon the outer capsule is relatively longer than the flange upon the inner capsule and is designed to be crimped into the sealing recess at the base of the bead 12 without causing a similar crimping action to be exerted upon the inner flange 28.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. The combination with a receptacle of glass or similar material provided with an annular bead adjacent the mouth, of inner and outer sealing capsules of thin sheet material, the outer capsule having a rupturing tongue and a sealing flange of sufficient depth to extend completely about the bead and be forced into a recess at the bottom thereof and the inner capsule having a straight sided annular flange of less depth fitting substantially closely about the bead and terminating short of the lower edge of the outer sealing

flange, whereby the inner capsule is held onto the bottle irrespective of whether the outer capsule is applied or removed from the bottle, and a sealing disk of compressible material received and fitting within the inner capsule and compressed thereby against the edge of the bead surrounding the mouth of the receptacle. 40 45

2. The combination with a receptacle having an annular bead surrounding the mouth, of an outer capsule of thin sheet metal having a rupturing tongue in the upper portion and an annular sealing flange extending about the bead and pressed inwardly into engagement with the receptacle at the base of the bead, an inner capsule of thin sheet material having a relatively shorter annular flange fitting closely about the outer periphery of the bead and directly engage said bead and terminating a sufficient distance above the sealing flange to permit crimping of the outer sealing flange without a like crimping of the inner flange, but providing a sufficient engaging surface with the bead of the bottle to hold the capsule on the bottle irrespective of whether the outer capsule is applied or removed, and a disk of compressible material received within the inner capsule and compressed thereby against the surface surrounding the mouth of the receptacle, the inner capsule together with the compressible disk serving to hermetically seal the receptacle when the outer capsule is in place and as a removable seal or closure after the outer capsule has been detached. 50 55 60 65 70
